DOUBLE BLANK EJECTOR FOR CAN BODY FORMING MACHINES

Filed Aug. 25, 1939

5 Sheets-Sheet 5

from the intermediate roll 46 to permit normal passage of single body blanks will be shifted so that its nose portion 51 engages with that roll, and as the double or superposed blank passes through the rolls 45, 46 and is diverted upwardly by the breaker steel 48 it will engage the plate 57, 55 and be ejected into the ejector blank receiver. This ejection of double or superposed can body blanks is accomplished without stopping the body maker or interrupting the continuous feed of the body blanks from the stack or reservoir, and it will be noted that grain breaking rolls are utilized in performing the ejecting function.

It is, of course, to be understood that the details of structure and arrangement of parts may be variously changed and modified without departing from the spirit and scope of my invention.

Having thus described the invention, what I claim as new and desire to secure by Letters Patent, is—

1. In a can body maker wherein is provided a feed line, means for feeding blanks step-by-step along the line, a set of grain breaking rolls, and means for normally presenting blanks from the feed line to the rolls and for returning them through said rolls to said feed line; means for detecting the presence of double or superposed blanks, and means controlled by said detecting means and movable into and out of engagement with said roll set for diverting and preventing return through said roll set of double or superposed blanks or for permitting and grinding normal return through said roll set of single blanks.

2. In a can body maker wherein is provided a feed line, means for feeding blanks step-by-step along the line, a set of grain breaking rolls, and means for normally presenting blanks from the feed line to the rolls and for returning them through said rolls to said feed line; means for detecting the presence of double or superposed blanks, a deflector plate movable into and out of engagement with said roll set for diverting and preventing return through said roll set of double or superposed blanks or for permitting and guiding normal return through said roll set of single blanks, counterbalancing means for moving the plate in one direction, and electrically actuated means controlled by said detecting means for moving the plate in the opposite direction.

3. In a can body maker wherein is provided a feed line, means for feeding blanks step-by-step along the line, a constantly engaged set of grain breaking rolls composed of three rolls superposed with their axes in parallel relation, and means for normally presenting blanks from the feed line to the rolls to pass between the intermediate roll and the lower roll and around the intermediate roll and beneath the upper roll back to the feed line; means for detecting the presence of double or superposed blanks, and means controlled by said detecting means for diverting such double or superposed blanks to prevent their return between the intermediate and upper rolls, said last-named means including a deflector plate movable into and out of close proximity with the intermediate roll.

4. In a can body maker wherein is provided a feed line, means for feeding blanks step-by-step along the line, a constantly engaged set of grain breaking rolls composed of three rolls superposed with their axes in parallel relation,

and means for normally presenting blanks from the feed line to the rolls to pass between the intermediate roll and the lower roll and around the intermediate roll and beneath the upper roll back to the feed line; means for detecting the presence of double or superposed blanks, means controlled by said detecting means for diverting such double or superposed blanks to prevent their return between the intermediate and upper rolls, said last-named means including a deflector plate movable into and out of close proximity with the intermediate roll, spring means normally holding the deflector plate out of close proximity with said intermediate roll, and electrically actuated means for forcing said deflector plate into said close proximity with the intermediate roll.

5. In a can body maker, blank guiding means, blank moving means, opposed power driven grain breaking rolls between which said blanks normally are moved, an ejector for ejecting double or superposed blanks from their usual path of travel between said rolls, electrically actuated means for moving the ejector to an ejecting position with relation to said rolls, counterbalancing means normally holding the ejector out of ejecting position, an energizing circuit including a normally open switch for controlling actuation of the ejector, a detector member disposed in spaced opposition to a portion of the guiding means and normally permitting passage of blanks, but movable upon engagement by double or superposed blanks to close said switch and effect an ejection of said double or superposed blanks, said detector member comprising a pivotally mounted bell crank lever having one arm presented in opposition to said guiding means portion and its other arm opposed to said switch, and an adjustable stop screw means for adjusting the lever about its pivot to simultaneously vary the spaced relation of the respective lever arms with the guiding member portion and the switch, respectively.

6. In a can body maker wherein is provided a constantly engaged set of grain breaking rolls, and devices for feeding blanks through the machine including means for presenting said blanks to said rolls; means for detecting the presence of double or superposed blanks, a blank guiding and ejecting element normally spaced from one of said rolls for guiding single blanks thereabout and movable into proximity with one of said rolls for diverting a detected blank double from the course it would ordinarily follow and ejecting the same, and means controlled by said detecting means for placing said element in its blank double diverting position.

7. In a can body maker, blank guiding means, blank moving means, opposed power driven grain breaking rolls between which said blanks normally are moved, an ejector for ejecting double or superposed blanks from their usual path of travel between said rolls, electrically actuated means for moving the ejector to an ejecting position with relation to said rolls, counterbalancing means normally holding the ejector out of ejecting position, an energizing circuit including a normally open switch for controlling actuation of the ejector, and a detector member disposed in spaced opposition to a portion of the guiding means, and normally permitting passage of blanks, but movable upon engagement by double or superposed blanks to close said switch and effect an ejection of said double or superposed blanks, said ejector having two roll opposing

surfaces one effective normally to aid in guiding single blanks in normal travel through the rolls and the other effective when the ejector is moved to its ejecting position to divert double blanks from said usual path and out of the machine.

8. In a can body maker wherein is provided a feed line, means for feeding blanks step-by-step along the line, a constantly engaged set of grain breaking rolls composed of three rolls superposed with their axes in parallel relation, and means for normally presenting blanks from the feed line to the rolls to pass between the intermediate roll and the lower roll and around the intermediate roll and beneath the upper roll back to the feed line; means for detecting the presence of double or superposed blanks, and means controlled by said detecting means for diverting such double or superposed blanks to prevent their return between the intermediate and upper rolls, said last-named means including a deflector plate movable into and out of close proximity with the intermediate roll and including a surface normally effective to guide single blanks about the intermediate roll and between it and the uppermost roll and another surface effective when said plate is moved into close proximity with said intermediate roll to divert double blanks out of the machine.

9. In a can body maker wherein is provided a feed line, means for feeding blanks step-by-step along the line, a constantly engaged set of grain breaking rolls composed of three rolls superposed with their axes in parallel relation, and means for normally presenting blanks from the feed line to the rolls to pass between the intermediate roll and the lower roll and around the intermediate roll and beneath the upper roll back to the feed line; means for detecting the presence of double or superposed blanks, means controlled by said detecting means for diverting such double or superposed blanks to prevent their return between the intermediate and upper rolls, said last-named means including a deflector plate movable into and out of close proximity with the intermediate roll and including a surface normally effective to guide single blanks about the intermediate roll and between it and the uppermost roll and another surface effective when said plate is moved into close proximity with said intermediate roll to divert

50 double blanks out of the machine, spring means normally holding the plate in its single blank guiding position, and electrically actuated means for forcing said plate into its double blank diverting position.

10. In a can body maker wherein is provided a feed line, means for feeding blanks step-by-step along the feed line, a set of constantly engaged and rotating grain breaking rolls composed of three rolls superposed with their axes in parallel relation, means for presenting blanks from the feed line to the rolls to pass between the intermediate roll and one of the engaging rolls, blank guiding and deflecting means normally positioned relative to said rolls so as to be effective to direct single blanks passing between said intermediate roll and said one engaging roll about said intermediate roll and between it and the other engaging roll thereby to break grain in said single blanks and return them to the feed line, means for detecting the presence of double or superposed blanks, and means controlled by said detecting means for displacing the blank guiding and deflecting means from its normal single blank directing position and repositioning it in a double blank deflecting position relative to said rolls each time a double blank is detected thereby to cause said detected double blank to be ejected from the machine by the intermediate and said one engaging roll.

11. In a can body maker, a feed line, means for feeding blanks step-by-step along the line, a set of grain breaking rolls presenting a first set of surfaces in rolling contact effective to feed blanks from the line and a second set of surfaces in rolling contact effective to return the blanks to the line, means for presenting blanks from the feed line to the first set of surfaces, means normally effective for directing between said second set of surfaces blanks being moved by said first set of surfaces for return to the feed line, and means including a shiftable diverter surface automatically effective each time double blanks are presented for passage through said first set of surfaces for diverting said double blanks from said normal diverting means so that the feed function of said first set of surfaces will be effective to eject said double blanks from the machine.
